(57) **CLAIM**

The ornamental design for an fitted garment cover for concealing urostomy, ileostomy or colostomy pouch, as shown and described.

DESCRIPTION

FIG. 1 is a perspective view of a fitted garment cover for concealing urostomy, ileostomy or colostomy pouch showing my new design.

FIG. 2 is a perspective view thereof;

FIG. 3 is a front elevational view thereof;

FIG. 4 is a rear elevational view thereof;

FIG. 5 is a left side elevational view thereof; and,

FIG. 6 is a front elevational view thereof.

The broken line surrounding the claimed design is shown for environmental structure and forms no part of the claimed design. The broken line on the surface of the claimed design represents top-stitching.
